UNITED STATES PATENT OFFICE.

FERNANDO CASABLANCAS, OF SABADELL, SPAIN.

DRAWING MECHANISM FOR TEXTILE ROVINGS, WITH FEEDING BELTS.

1,416,608.

Specification of Letters Patent.

Patented May 16, 1922.

Application filed February 17, 1921. Serial No. 445,782.

To all whom it may concern:

Be it known that I, FERNANDO CASABLANCAS, a subject of the King of Spain, residing at Sabadell, Spain, have invented certain new and useful Improvements in Drawing Mechanism for Textile Rovings, with Feeding Belts; and I do hereby declare the following to be a full, clear, and exact description of the invention, such as will enable others skilled in the art to which it appertains to make and use the same.

The present invention relates to improvements in spinning frames in which slack endless belts are employed to conduct the roving or textile fibers from the feeding to the drawing rollers.

An object of the invention is to avoid any slippage of the belt and consequently of the roving whereby the fibers will be uniform and regular.

In prior mechanisms for drawing apparatus, in which belts or straps of this character are used, irregularities in the drawing of the threads of fibers result on account of this slippage which occurs casually and there is no way in which to take this slippage into account or to compensate for its action.

Many attempts have been made heretofore to secure the driving of the belt without any slippage between the same and its driving element. Some attempts have involved the use of ribbed driving rollers with the ribs in engagement with the belt, others have proposed to use engraved rollers and to provide ribs or depressions upon the belt to correspond with the formation given the rollers, and experiments have also been made to effect this result by the use of rollers covered with carding tape. However none of these proposed remedies has been found satisfactory in practice and the commercial thread is not shown to be improved thereby.

The present invention therefore aims to overcome the difficulties of the former method and apparatus and to improve the quality of the article obtained by securing an accurate and uniform driving relation between the drive roller and its belt without incurring any slippage whatsoever.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a vertical section of an apparatus constructed according to the present invention, and,

Fig. 2 is an enlarged cross section through the driving roller.

Referring more particularly to the drawings, 2 and 3 designate the feeding rollers 65 and 12 and 13 the drawing rollers, there being slack belts 5 and 9 disposed to bear upon opposite sides of the roving 1 as it passes from the feeding to the drawing rollers. The belts 5 and 9 extend respectively about 70 the idle roller 4 and the drive roller 8 and are guided upon their exterior outer runs by rods 6 and 10 and by the guide plates 7 and 11.

The roller 8 extends through the length of 75 the machine and is connected at one of its ends to a driving source which imparts rotation to it. The upper roller 4 receives rotation by contact through the belts with the driving roller 8. The weight of the upper 80 roller 4 causes a close contact between the rollers. In spinning frames as heretofore constructed the belts 5 and 9 are smooth both upon the inner and outer faces and this results in the slipping of the belts and particularly the belt 9 upon the roller 8.

According to the invention, the roller 8 which drives the lower belt 9 has its surface cut or engraved in the form of saw teeth as shown on an enlarged scale in Fig. 2. These 90 saw teeth are inclined as shown and they have their pointed ends extending forwardly in the direction of rotation of the roller 8 which is counter-clock-wise as viewed in both figures of the drawing. If 95 desired, the upper roller 4 may also be provided with similar saw teeth, although this is not necessary. The cutting of the saw teeth may be accomplished by a shaping engine or by other similar machine. These 100 rollers, as indicated in Fig. 2, may comprise a central core upon which a washer or collar is fitted with saw teeth thereon.

The rotation of the roller will cause the forward projecting ends of the teeth to bite 105 into the belt throughout a large area as indicated in Fig. 1 without however doing injury to the belt due to the small penetration at a great number of points.

In accordance with this device, the slip- 110

page is shown to be negligible and the roving is shown also to be of a superior uniformity.

It is obvious that various changes and modifications may be made in the details of construction and design of the above specifically described embodiment of this invention without departing from the spirit thereof, such changes and modifications being restricted only by the scope of the following claims.

What is claimed is:

1. A drawing mechanism comprising a pair of feeding rollers, a pair of drawing rollers situated apart from the feeding rollers, a pair of slack belts between the drawing and feeding rollers and adapted to bear yieldingly upon the roving at opposite sides, an idle roller in the upper of said belts bearing upon the lower belt, and a driven roller engaged through the lower belt beneath said upper roller, said drive roller having inclined teeth thereon with points projecting at an angle, such angle being in the direction of rotation of the teeth, such teeth adapted to engage in the belt to drive the lower belt without slipping.

2. In a drawing apparatus, a pair of feeding rollers, a pair of drawing rollers situated apart therefrom, a pair of slack belts disposed at opposite sides of the roving and bearing yieldably thereupon between the feeding and drawing rollers, said slack belts having unoccupied front bight portions, means for engaging the outer runs of the belts to guide the same, said belts adapted to be driven in opposite directions and coming together upon the roving at their inner runs, an idle roller adapted to occupy the rear bight of the upper belt and bearing upon the lower belt, and a positively driven roller occupying the rear bight of the lower belt and having saw teeth thereon with the inclined points of the saw teeth extending in the direction of rotation of the roller and adapted to be driven by the rotating motion into the lower belt and to prevent loss of movement therebetween.

In testimony whereof, I affix my signature, in presence of two witnesses.

FERNANDO CASABLANCAS.

Witnesses:
